(57) **CLAIM**

The ornamental design for a disinfection light, as shown and described.

DESCRIPTION

FIG. 1 is a right side, top perspective view of a disinfection light, showing my new design;
FIG. 2 is left side, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.
The broken lines in the figures illustrate portions of the disinfection light that form no part of the claimed design.

1 Claim, 8 Drawing Sheets
